UNITED STATES PATENTS OFFICE.

SAMUEL F. QUAY, OF FLAGSTAFF, ARIZONA.

CONVEYER CLEAT OR FLIGHT.

1,169,351.

Specification of Letters Patent. Patented Jan. 25, 1916.

Application filed May 19, 1915. Serial No. 29,153.

To all whom it may concern:

Be it known that I, SAMUEL F. QUAY, a citizen of the United States, and resident of Flagstaff, in the county of Coconino and State of Arizona, have invented certain new and useful Improvements in Conveyer Cleats or Flights; and I do hereby declare the following to be a full, clear, and exact description of the invention, such as will enable others skilled in the art to which it appertains to make and use the same.

My invention relates to an improved flight or cleat for conveyers of the chain type.

It is one of the objects of my invention to provide a flight or cleat which has a lower member of substantially the width of the trough in which the chain runs, and an upper member coöperating therewith in such a manner that the flight or cleat is easily assembled or disassembled, and is yet securely fastened in place when it is assembled.

Another object of my invention is the provision of a flight or cleat of the above-mentioned type of which the members are fastened together without the use of a bolt or rivet.

Still another object of my invention is the provision of a flight or cleat comprising a lower member provided with a link-receiving groove in one side intermediate its ends and having the opposite side cut out to a horizontal plane to a point substantially above said groove and thus curved upwardly in a 90 degree arc, the upper member being so shaped that it coöperates with the cut-out in the lower member in such a manner that it may be placed against the link and rotated in a seated position without resistance.

A still further object is the provision in a flight or cleat of this type of tongue and cotter-pin means for securing the members comprising the flight or cleat together.

Referring to the drawings annexed hereto, and in which I have illustrated a preferred embodiment of my invention: Figure 1 illustrates in perspective the upper member of the flight or cleat. Fig. 2 illustrates in perspective the lower member of the flight or cleat. Fig. 3 is an elevation view of the upper and lower members in position on the link of a chain to be assembled. Fig. 4 is a view similar to Fig. 3 but showing the upper member partially rotated into the position. Fig. 5 is a view similar to Figs. 3 and 4, but showing the upper member wholly rotated into its seated position, and secured

in such position by cotter-pin fastening means. Fig. 6 shows the position of the trough, chain and flights or cleats when a conveyer of this type is set up ready for use. 60

Referring particularly to the drawings, the lower member 1 illustrated in Fig. 2 is of length substantially the width of the trough in which the conveyer runs, as illustrated best in Fig. 6. The lower side 2 of this lower member is provided intermediate of its ends with a link-receiving groove 3, whereas the upper side is cut away on a horizontal plane to a point substantially above the center of the groove 3, and is then cut away to form 70 a surface representing an arc of 90 degrees. At the outer end of this lower member 1 is formed a boss 4 having a curved tongue-receiving recess 5 and a transverse pin hole 6. At the edge 7 of the curved portion of the 75 upper side is a recess 8.

The upper member 9 is of a length to fit in the cut-away portion of the lower member, and in its upper side has a link-receiving groove 10. The lower side thereof is 80 shaped at its inner end as shown at 11 to fit upon that portion of the surface of the cut-away portion of the member 1 representing a 90 degree arc, while the rest of the lower surface of the member 9 is shaped to seat 85 against the horizontal cut-away portion. The member 9 has on its lower face a spur 12 which, as will be seen by referring to Figs. 4 and 5, when the upper member is in the seated position engages the recess 8 in 90 the lower member and prevents lateral displacement of the upper and lower members with respect to each other, and also receives the shearing stresses which may be exerted 95 upon the fastening means during the operation of the conveyer.

The fastening means comprises a tongue 13 integral with the upper member 9 and which, when the upper member is rotated to its seated position, enters the receiving 100 recess 5 in the boss 4. The tongue 13 is provided with a pin hole 15 which, when the tongue is in the recess 5, aligns with the pin hole 6. In order to hold this tongue in the recess, and thereby lock the upper 105 and lower members together, a split cotter-pin 16 is inserted in the pin hole 6 and extends through the pin hole 15 in the tongue 13, its free ends being bent apart, as shown in Fig. 5, to retain the pin in place. 110

In placing the flight or cleat in a chain, the reduced portion of the lower member is

inserted in the link until the link-receiving groove 3 engages the link and the lower member drops into place. The upper member is then placed against the upper part of 5 the link, in the position shown in Fig. 3, and is rotated in the direction indicated by the arrows in Figs. 3 and 4 to a position where it seats against the cut-away portion of the lower member, or to that position 10 shown in Fig. 5. The split cotter-pin 16 is then inserted and the ends bent apart as shown.

In order to remove the flight or cleat, it 15 is only necessary to withdraw the cotter-pin 16 and rotate the upper member 9 in a direction opposite to that which seats it in place.

In order to reinforce the lower and upper members, that portion of each member containing the link-receiving groove is made 20 of heavier stock than the rest. Also the lower member may be provided with reinforcing ribs such as 17.

While I have herein shown and described 25 one specific embodiment of my invention, it is to be understood that I do not wish to be limited thereto except for such limitations as my claims import.

I claim:

1. The combination with a conveyer chain, 30 of a flight comprising a lower member having a link-receiving groove, a boss integral therewith and having a curved tongue-receiving recess, an upper member seating on said lower member and having a link-receiving groove coöperating with said first-mentioned groove to retain said flight or 35

cleat in a link, a tongue integral with said upper member and entering said tongue-receiving recess to hold said members in position, and means for securing said tongue 40 in said recess, substantially as described.

2. The combination with a conveyer chain, 45 of a flight comprising a lower member having a link-receiving groove in one side intermediate its ends and the opposite side thereof of cut out on a horizontal plane to a point substantially above said groove and thence curved upwardly in a 90 degree arc, a boss integral with said lower part and having a tongue-receiving recess therein, an upper 50 part provided on its upper side with a link-receiving groove for coöperation with said first-mentioned groove to retain said flight or cleat in a link and having its lower side shaped to seat against the cut-out or said 55 lower member whereby the inner end of said upper member may be placed in a vertical position against the link and rotated into its seated position, a tongue on said lower member arranged to enter said tongue-receiving recess to retain said members in seated relation, and means for securing said tongue in said recess, substantially as described.

In testimony whereof, I have signed this 60 specification in the presence of two subscribing witnesses.

SAMUEL F. QUAY.
